DESCRIPTION

U.S. PATENT DOCUMENTS

FIG. 1 is a front perspective view of our design for an attachment device for floor shaving systems;

FIG. 2 is a back perspective view thereof;

FIG. 3 is a back elevation view thereof;

FIG. 4 is a front elevation view thereof;

FIG. 5 is a right view thereof;

FIG. 6 is a left view thereof;

FIG. 7 is a top plan view thereof; and,

FIG. 8 is a bottom plan view thereof.
